UNITED STATES PATENT OFFICE,

JAMES H. GARRATT, OF ROCHESTER, NEW YORK, ASSIGNOR OF ONE-HALF TO
HALBERT GREENLEAF BROOKS, OF ROCHESTER, NEW YORK.

EJECTING MECHANISM FOR PRESSES.

1,108,898.

Specification of Letters Patent.

Patented Sept. 1, 1914.

Application filed August 2, 1913. Serial No. 782,583.

To all whom it may concern:

Be it known that I, JAMES H. GARRATT, of Rochester, in the county of Monroe and State of New York, have invented certain new and useful Improvements in Ejecting Mechanism for Presses; and I do hereby declare the following to be a full, clear, and exact description of the same, reference being had to the accompanying drawings, 10 forming a part of this specification, and to the reference-numerals marked thereon.

My invention relates to an ejecting or knock-out mechanism for presses, more particularly with reference to sheet metal die 15 presses and the like, and it has for its primary object the provision of means for automatically ejecting or discharging the work after the die has completed its operation, and during its upward movement, so that 20 the operator may give his entire attention to the positioning of a blank for the next succeeding operation.

A further object of my invention resides in arranging and connecting the mechanism 25 in such a manner that the downward movement of the die plunger may be utilized to set in operation and effect actuation of the ejector, which however does not make its operative stroke until immediately after the 30 die has commenced its upward stroke.

To these and other ends, the invention consists in certain improvements and combinations of parts, all as will be hereinafter 35 more fully described, the novel features being pointed out in the claims at the end of the specification.

In the drawings: Figure 1 is a front elevation, with parts broken away, of a die press, showing the application of one embodiment of the invention; Fig. 2 is a side elevation of the ejecting mechanism and feeding receptacle; Fig. 3 is a plan view of the parts shown in Fig. 2; Fig. 4 is a detailed sectional view, on the line 4-4 of Fig. 6, of a portion of the ejecting mechanism, showing the operating device; Fig. 5 is a similar view on the line 5-5 of Fig. 8; Fig. 6 is a bottom plan view of the parts of the ejecting mechanism, as they appear 10 in normal position; Fig. 7 is a similar view showing the position of the parts when the operating device has completed its stroke, and just prior to the release of the ejector; Fig. 8 is a similar view showing the posi-

tion of the parts when the ejector has completed its movement in one direction and is about to be returned to its normal position, by the actuator; Fig. 9 is a sectional view on the line 9-9 of Fig. 6 looking toward the left of the figure; Fig. 10 is a sectional view on the line 10-10 of Fig. 6; Fig. 11 is an enlarged view in section of the lock or escapement mechanism, on the line 10-10 of Fig. 6, looking toward the right of the figure, and showing the parts in normal position; Fig. 12 is a similar view showing the position of the parts after the initial movement of the ejector, and Fig. 13 is a similar view showing the position of the parts after the release of the ejector and immediately prior to its operation.

Similar reference numerals in the several figures indicate the same parts.

For a general understanding of my invention, it may be stated that in the operation of die presses and punches and similar machines, it has been necessary for the operator to manually knock the work from its support after the completion of each operation and before another blank can be inserted for the next succeeding operation. This requires considerable dexterity, and involves a great deal of danger as the work not infrequently adheres more or less to the plunger and is carried upwardly therewith, often resulting in injury to the fingers of the operator. It is my purpose therefore to relieve the operator entirely of this duty by making the discharge of the work automatic after each operation, so that he may devote all his attention to the feeding in of fresh blanks. This results in enabling the work to be done much faster than heretofore, giving increased efficiency to the machine, and also effectually preventing any possibility of injury to the operator from this source. The invention is susceptible of various applications and it is to be understood that the present embodiment is shown for the purposes of illustration only, and is not intended as limiting the scope of my improvement in any particular to a specific construction.

In the present arrangement, which I have found to be a practicable and successful adaptation of the invention, 1 designates the plunger of the press, which may be of the usual form of construction, and is provided

with a die 2 operating to engage a blank on the work support 3. The plunger 1 is further provided with an arm 4, which may or may not be removable, as desired, and carries a downwardly extending arm 5 arranged to effect the operation of the ejecting mechanism in a manner which will appear more clearly hereinafter.

The ejecting mechanism is arranged in a 10 housing 6 which is preferably mounted on legs or standards 7, to one of which is secured a locking bar 8.

9 designates a feed basket or a hopper having a mouth 10 through which the blanks 15 may be fed onto the work support, while 11 designates a protective wall or grating extending upwardly from the basket at its ends, and at the side adjacent to the mouth 10 so as to prevent the hands of the operator 20 from coming in contact with the plunger of the machine where it engages the work. The basket is provided with forwardly extending legs 12 which engage recesses 13 in the locking bar 8 and are held in engagement therewith by the pivoted latches 14 arranged upon the bar 8 and coöperating with recesses in the legs 12.

The ejecting mechanism embraces an ejector 15 which has an oscillating movement 30 across the top of the work support and between it and the die plunger, the parts being so timed as to effect movement of the ejector at an instant just after the completion of the downward stroke of the die and 35 during its initial upward movement, whereby the ejector will engage the work whether it be resting upon the work support or adhering to the die. To this end, the ejector 15 is mounted upon an ejector member 16 40 which is arranged for an oscillating movement about the pivot post 17. Also mounted on the pivot post 17 is an actuator 18 arranged adjacent to the ejector member 16 and having a shoulder 19 against which the latter 45 abuts, while 20 is an arm upon the actuator to which is connected a spring 21, the latter having its opposite end secured to a corresponding arm 22 on the ejector member. It will be observed that the lower faces of the 50 arms 20 and 22 are in the same horizontal plane and that the spring 21 tends to draw the ejector member toward the actuator when the parts are in the position shown in Fig. 7. The actuator 18 carries an ear 23 55 to which is connected a spring 24 having its other end attached to a post 25. The last mentioned spring 24 serves to effect the return of the actuator, and of the ejector member carried therewith, to their normal positions, causing the quick return movement of 60 the ejector after it has discharged the work, as will be described more clearly presently.

26 is a carrier, also pivotally mounted on the post 17 with the ejector member. The 65 carrier is provided with an ear 27 to which

is engaged a spring 28, the latter also being connected to the post 25 and operating to return the carrier to its normal position as shown in Fig. 6. The carrier 26 is provided with a beveled edge 29 with which the operating device coöperates. The latter preferably comprises a plunger which is mounted for reciprocating and rotating movement, and is designated at 30.

31 is a cam slot coöperating with a projection 32 on the housing, while 33 is a cam face at the lower end of the plunger which engages the beveled edge 29. As downward movement is imparted to the operating device, or plunger, a corresponding swinging movement of the carrier is effected, and the rotating motion of the plunger causes the cam face 33 to follow the bevel edge 29 closely, and to remain constantly in the same relation thereto. The plunger is adjustable, to provide for operating with different thicknesses of work, and to this end it has a threaded opening at the top which receives the threaded stem 35, the latter being provided with a bearing 36 on its upper surface 90 arranged to be engaged by the arm 5 when the plunger of the press travels downwardly.

37 is a lock nut for holding the stem 35 in its adjusted position, and 38 is a spring for returning the plunger to its normal position upon the upward movement of the die.

The actuator 18 is normally held to the carrier 26 by a locking means, preferably consisting of a pawl 39 which is pivotally mounted at 40 upon the carrier and engages 100 a coöperating recess or notch 41 on the actuator. The pawl 39 is held in operative engagement by means of a spring 42, its movement being limited by a stop 43. The ejector member 16 carries a latch 44 which is pivotally mounted at 45 and is adapted to engage on opposite sides of the pawl 39 as shown in Figs. 6 and 8 respectively. The latch 44 carries a tail piece 46 which is engaged by a stop 47 when the parts are in normal position as shown in Fig. 6, whereby the latch is positioned to effect engagement of the pawl 39 with the actuator.

48 is a leaf spring positioned on the ejector member, engaging the tail piece 46, 115 so as to effect movement of the latch 44 to the position shown in Fig. 8, in order to disengage the pawl 39 from the actuator. This operation releases the actuator and permits it to return the ejector member to its normal position quickly, and while the carrier is at the beginning of its return movement.

The ejector member is held in normal position by a lock which preferably embodies 125 an escapement mechanism operating in such a manner as to release the ejector for a partial and limited movement when the die reaches the limit of its downward stroke, and to entirely release the ejector for its 130

operative and return movement, the instant the die commences its upward stroke and before it has moved an appreciable distance from the work support. To this end, the 5 ejector member carries a pair of teeth 49 and 50 arranged in the manner shown in Figs. 11 to 13 inclusive, and mounted on the extension 51. Arranged for coöperation with the teeth 49 and 50 is a tooth 52 carried 10 by the locking lever 53, which is pivotally mounted on the post 54 and carries an arm 55. The locking lever 53 is loosely pivoted so as to have a movement in two planes, its vertical movement being controlled by the 15 leaf spring 56 while its lateral movement is resisted by the spring 57.

58 is a post for determining the position of the locking lever when in its normal relation to the remaining parts.

20 The carrier 26 is provided with an extension or arm 59 which coöperates with the arm 55 on the locking lever in such a manner as to rock the latter on a horizontal pivot, moving it in a vertical plane and 25 thereby removing the tooth 52 from its normal position as shown in Fig. 11 where it engages the tooth 49, to the plane of the tooth 50 causing it to assume the position shown in Fig. 12, and permitting the ejector 30 member a corresponding lateral movement. It will be seen that the parts retain the position last described as long as the extension of the carrier is in engagement with the arm of the locking lever, and as soon as the latch 35 ter is released, it assumes its normal position, releasing the tooth 52 from engagement with the tooth 50 so that the parts take the position shown in Fig. 13, and the ejector member is free to be carried toward 40 the actuator by means of the spring 21. When the ejector member reaches the shoulder 19 of the actuator, the latch 44 will have released the pawl 39 from engagement with the actuator, and the latter is then free to 45 return to its normal position under the action of the spring 24, thus carrying the ejector and the actuator back to the position shown in Fig. 6. The return movement of the carrier is governed by the upward movement 50 of the plunger 30, which in turn depends upon the return movement of the die plunger.

The operation of the machine, briefly described, is as follows: With the parts arranged as shown in Fig. 6, the plunger 30 is depressed by the downward movement of the die plunger and effects a corresponding swinging movement of the carrier 26, the actuator 18 being moved with the carrier 55 during the last-mentioned operation by the pawl 39 until the parts assume the position shown in Fig. 7. At this time, the extension 59, has engaged the arm 55 on the locking lever 53, moving it in a vertical plane 60 so as to release the tooth 49 and to engage

the tooth 50. This is the position when the die is at the downward limit of its stroke. As soon as it commences to move upwardly, the carrier is permitted a slight return movement, under the action of the spring 28. 70 This frees the locking lever 53, and the latter is returned to its normal position by the spring 56, which movement releases the tooth 50 and allows the spring 21 to move the ejector laterally until the ejector member 75 comes into engagement with the shoulder 19 of the actuator. This movement of the ejector causes the work to be swept from the work support into any convenient receptacle that may be provided, the ejector 80 being immediately returned to its normal position, in order to permit the operator to position a blank for the next succeeding operation while the die is completing its upward movement. At the limit of the forward movement of the ejector, the actuator 85 is released by the engagement of the latch 44 with the pawl 39 as shown in Fig. 8, the movement of the parts being so quick that the contact between said latch and pawl is 90 sufficient to permit the actuator to be withdrawn before the pawl 39 can recover its normal position. The spring controlling the actuator thereupon returns the latter to its first position, and with it the ejector member. 95 The latch 44 is engaged by the stop 47 when the ejector member reaches its normal position, causing it to assume the position shown in Fig. 6. As the plunger 30 arises upon the upward movement of the die, the 100 carrier 26 is returned to its normal position. The pawl 39 again engages the notch 41 in the actuator, and the parts are ready for the next operation.

Although I have described the invention 105 as embodied in what seems to be a preferred form, I do not limit myself to any of the details or arrangements herein set forth but intend to cover by this application any modifications and changes that may come generally within the scope of my invention, and of the claims of this application.

I claim as my invention:

1. In an ejecting mechanism for die presses and the like, the combination with 115 an oscillatory carrier, of an oscillatory ejector member movable independently of the carrier, an actuator mounted on the carrier, a reciprocatory operating device, and means actuated by the operating device for 120 imparting an oscillatory movement to the ejector member.

2. In an ejecting mechanism for die presses and the like, the combination with 125 an oscillatory carrier, of an operating plunger mounted for reciprocating and rotative movement and coöperating with the carrier, an oscillatory ejector member movable independently of the carrier, and an actuator mounted on the carrier and adapted to be 130

- 5 moved independently thereof to effect movement of the ejector member.
- 10 3. In an ejecting mechanism for die presses and the like, the combination with a carrier, of an oscillatory carrier, of a reciprocating operating device coöperating with the carrier, an oscillatory ejector member movable independently of the carrier, and an actuator mounted on the carrier and arranged to effect movement of the ejector member.
- 15 4. In an ejecting mechanism for die presses and the like, the combination with a carrier, of a reciprocating operating device coöperating with the carrier, an oscillatory ejector member, an actuator mounted on the carrier and movable independently thereof, and a locking means disposed on the carrier and coöperating with the actuator to hold it against movement.
- 20 5. In an ejecting mechanism for die presses and the like, the combination with a carrier, of a reciprocating operating device coöperating with the carrier, an oscillatory ejector member, an actuator mounted on the carrier and movable independently thereof, means on the carrier for locking the actuator, and means on the ejector member for

operating said locking means to release the actuator from the carrier.

25 6. In an ejecting mechanism for die presses and the like, the combination with a carrier, of an operating device coöperating with the carrier, an oscillatory ejector member, and a lock for the ejector member, the carrier being arranged to engage said lock to effect release of the ejector member.

30 7. In an ejecting mechanism for die presses and the like, the combination with a carrier, of an operating device coöperating with the carrier, an oscillatory ejector member, a lock for the ejector member, the carrier being arranged to engage said lock to effect release of the ejector member, an actuator mounted on the carrier, locking means disposed on the carrier and coöperating with the actuator to hold it against movement on the carrier, and means arranged on the ejector member to effect release of the actuator.

JAMES H. GARRATT.
